UNITED STATES PATENT OFFICE.

JOHN L. WHEELER, OF ST. LOUIS, MISSOURI, ASSIGNOR TO THE MEASUREGRAPH COMPANY, OF ST. LOUIS, MISSOURI, A CORPORATION OF DELAWARE.

RESETTING MECHANISM.

Application filed June 28, 1922. Serial No. 571,639.

To all whom it may concern:

Be it known that I, JOHN L. WHEELER, a citizen of the United States, residing in the city of St. Louis and State of Missouri, have invented new and useful Improvements in Resetting Mechanism, of which the following is a specification.

This invention relates to resetting mechanisms, and the invention is particularly applicable to odometers. While features of the invention may be applied to odometers of other kinds, the invention is especially useful when applied to an odometer having number wheels which are freely rotatable.

The general object of the present invention is to provide means to prevent the disturbance of the position of the number wheels when the automobile is backed, and also to provide a single hand-operated member for effecting the resetting movement of the indicator to zero, and for setting up the indicator to any desired reading.

This latter function is very useful in making a trip in an automobile, because sometimes the driver of the car will make a mistake in a turn, and find that he must return to a point where he left his proper route. When this occurs, he may wish to alter the reading of the trip register so as to eliminate the mileage which occurred when the automobile left the proper road. My invention is admirably adapted for use in such a case, because it enables the resetting mechanism to be readily employed to set the number wheels of the register to indicate any desired amount. A single hand-operated thumb-head may be used either to reset the number wheels to zero, or to alter the reading of the number wheels at will.

Further objects of the invention will appear hereinafter.

The invention consists in the novel features, and in the general combination of parts to be particularly described hereinafter, all of which contribute to produce a simple and efficient resetting mechanism. A preferred embodiment of my invention will be particularly described in the following specification, while the broad scope of my invention will be pointed out in the appended claims.

In the drawing—

Figure 1 is a front elevation of an odometer embodying my invention, and showing a portion of the dash surrounding the instrument;

Figure 2 is a side elevation of the instrument showing a portion of the dash in cross-section;

Figure 3 is a longitudinal section taken through the trip mechanism of the odometer, and illustrating my invention applied to the same, certain parts being broken away;

Figure 4 is a vertical section taken in the plane of the line 4—4 of Figure 3, and illustrating the pick-up mechanism which enables the number wheels to be picked up into a zero aligning relation;

Figure 5 is a cross-section taken in the plane of the line 5—5 and illustrating a one-way drive connection through which the regular driving movement is imparted to the wheel of lowest denomination by the running gear of the automobile;

Figure 6 is a detail plan illustrating two adjacent number wheels, and particularly illustrating the carrying mechanism to enable a wheel of lower denomination to carry over to a wheel of higher denomination;

Figure 7 is a detail view showing parts of the holding device which prevents disturbance of the number wheels when the automobile is driven backwards; this view shows some of the parts illustrated in Figure 3, but shows them in side elevation instead of in section;

Figure 8 is a plan of a ratchet disc which constitutes a detail of the holding device shown in Figure 7;

Figure 9 is a perspective illustrating details of a coupling connection for controlling the number wheels from the hand-operated member or thumb-head.

In the drawing, 1 represents the dash in which the odometer 2 is set so as to be within plain view of the driver. The instrument may include a speedometer with an indicating scale 3, but this forms no part of the present invention.

The odometer includes a total indicator, the number wheels of which are visible at the window 4 and a trip indicator, the number wheels of which are visible at

the window 5. My invention concerns the means for resetting and controlling by hand the number wheels of the trip indicator.

The preferred construction of the trip indicator is clearly shown in Figure 3 which is a vertical section on the line 3-3 of Figure 1. This indicator includes a plurality of mileage indicating number wheels 6, 7 and 8, the last of which is the wheel of lowest denomination, in the present instance, a fraction wheel. Three wheels will give the trip mechanism a capacity of one hundred miles, but if desired, there may be any number of these wheels to give the trip mechanism any capacity desired. The fraction wheel 8 is driven in the regular way in the forward direction by some part of the automobile, for example, a gear wheel (not illustrated) which meshes with a gear wheel 9 (see Figure 5). In other words, when the automobile is running forward, this gear wheel 9 is continuously rotated in the direction of the arrow shown in Figure 5. Therefore, this wheel 9 constitutes a part of the driving means for driving the wheel 8 of lowest denomination.

The driving means however, also includes a one-way driving connection preferably of the form indicated in Figure 5, and consisting of a thin disc 10 of metal, which is secured rigidly to the side of the number wheel 8, and has a resilient tongue or pawl 11 which may engage with any one of a plurality of notches or recesses 12 formed in the adjacent face of the gear 9; that is to say, this part 11 is merely a spring pawl against the end of which the end of one of the notches 12 thrusts to drive the wheel 8 in a forward direction. With this construction, it will be evident that if the wheel 8 were held against rotation, the gear wheel 9 could rotate backwardly if the automobile were backed, without rotating the number wheel 8. Any suitable carrying mechanism may be provided, for carrying between the wheels.

In order to enable this to be accomplished, rigid with the wheel 8, I provide a carrier wheel consisting of two discs 13 and 14, the former of which has two teeth 15, and the latter of which has a single tooth space 16, (see Figure 6). Extending along the side and parallel with the axis of rotation of the number wheels, I provide a carrier shaft 17 with loose carrier pinions, such as the pinion 18. At each rotation of the number wheel 8, the pinion 18 is rotated and imparts a movement to the number wheel 7 through one number space. This is accomplished by means of a gear wheel 19 rigid with the number wheel 7 and meshing with the pinion 18.

This mechanism is duplicated between the wheels 7 and 6 in order to enable the carrying to be effected from the unit-wheel to the

tens'-wheel. By a similar carrying device, the tens'-wheel carries over to the wheel of lowest denomination of the total indicator at the window 4.

I shall now describe the means which I provide for setting the wheels 6, 7 and 8 back to zero at will, and also for enabling these wheels to be set up to give any desired reading. In order to accomplish this, I provide an outer sleeve 20 which rigidly carries the wheel of lowest denomination, and also operates as a support for the driving gear 9, that is to say, the driving gear 9 is rotatably mounted on this sleeve. It is necessary to have the gear wheel 9 loose on this sleeve, otherwise the driving connection to this gear would prevent the rotation of the sleeve, and the number wheel 8, by hand.

I provide a hand-operated rotatable member mounted so as to shift into two positions, and I provide means for driving the outer sleeve from the hand-operated member in one of these positions to rotate the outer sleeve, and the lowest denomination wheel in the forward direction; and I provide means actuated by the hand-operated member in its other position, for rotating a pick-up shaft in a forward direction so as to co-operate with pick-up devices corresponding to each number wheel; that is to say, I provide means on the pick-up shaft which operates to hold the number wheels with their zeros aligning together, thereby enabling the hand-operated member to reset the number wheels to zero. In order to prevent the pick-up shaft from being rotated when the lowest-denomination wheel is being rotated in a forward direction by the hand-operated member, I provide special means to prevent such rotation, and this special means not only operates to prevent the pick-up shaft from rotating in the forward direction, but it also prevents the automobile from turning the number wheels from their position in case the automobile is driven backwards.

To this end, I provide a pick-up shaft which is in the form of a tubular shaft or inner sleeve 21 rotatably mounted within the outer sleeve 20. Each carrier wheel 13 is provided with a pick-up device consisting of a pawl 22 pressed by a spring 23; and opposite each pawl 22, the pick-up shaft 21 is provided with means to co-operate with the pawl to enable the pick-up shaft to engage the pawls to rotate the wheels 13. This means is in the form of a disc 24 with a notch having an inclined edge and an abrupt edge or shoulder 25 (see Figure 4).

The number wheels carry these pawls 22 at the same point with respect to the numbers on the wheels so that if the pick-up shaft is rotated in the direction of the arrow indicated in Figure 4, the shoulders 25 and the pawls 22 will co-operate to hold all the number wheels with their zeros aligning

together, and so that a further rotation in this direction will enable the number wheels to be all reset to zero simultaneously.

In order to place the rotatable hand-operated member in a position to be conveniently operated, I prefer to place it just in front of the dash 1 and construct it in the form of a milled thumb-head 26. This head is rigidly attached to an operating spindle or stem 27 which is mounted to slide in and out in a bushing 28. This bushing 28 is rotatable, but is held against sliding longitudinally. Furthermore, this bushing has a gear wheel 29 meshing with a gear wheel 30 attached to an extension sleeve 31 which is coupled to the outer sleeve 20 at the point 32 so that when the extension 31 is rotated, the outer sleeve 20 will also be rotated.

I provide clutch means for enabling the stem 27 to connect with the outer sleeve when the stem is pulled outwardly. For this purpose, the bushing 28 is provided with teeth, such as the tooth 33 which is adapted to be engaged by a cross-pin 34 carried by the stem, when the stem is pulled outwardly. The inner sleeve 21 is provided with a similar extension sleeve 35 which carries the gear wheel 36 meshing with a gear wheel 37 formed on the lower bushing 38.

I provide clutch means for enabling the stem 27 to connect with the inner sleeve 21 when the stem is pushed inwardly. For this purpose, the upper end of the bushing or sleeve 38 is provided with teeth, such as the tooth 39, which is adapted to be engaged by the cross-pin 34 when the stem is shoved in.

With this construction, it will be evident that if the stem 27 is pulled outwardly and is then rotated in a right-hand direction, the outer sleeve will be rotated in the direction indicated by the arrow in Figure 5, and this will rotate the wheel 8 in a forward direction, and this wheel will carry to the other wheels, thereby enabling the thumb-head 26 to advance the number wheels to any reading desired.

On the other hand, if the stem 27 is shoved in and then rotated in an anti-clockwise direction, the pick-up shaft 21 will be rotated in the direction of the arrow indicated in Figure 4, that is to say, in a forward direction. As the rotation progresses, all of the pawls 22 will come into engagement with the shoulders 25, thereby aligning all the zeros; by stopping the rotation at the proper point, the zeros of the wheels may be left in alignment at the window 5.

It will be evident that as the inner sleeve 21 fits rotatably in the outer sleeve 20, the rotation of the outer sleeve in the forward direction by means of the thumb-head 26 might impart rotation to the inner sleeve 21 and thereby unintentionally through the operation of the pick-up devices, align all the

number wheels to zero. The number wheel 6 is mounted on its corresponding outer sleeve 40, while the number wheel 7 is mounted on its corresponding outer sleeve 41.

As the outer sleeves 20, 40 and 41 are all freely rotatable on the inner sleeve 21, it will be evident that if the number wheel 8 were given a backward rotation by driving the automobile backwards, the rotation of its sleeve might operate to give a backward rotation to the inner sleeve 21 and thereby rotate the number wheels 6 and 7 in a backward direction. Such a backward rotation of the number wheel 8 could easily occur because the spring tongue 11 might easily cause the number wheel 8 to rotate back with the gear wheel 9. For this reason, it is necessary to provide means for preventing a backward rotation of the inner sleeve or pick-up shaft if the automobile is backed.

In order to provide means for preventing these accidental or unintentional rotations of the number wheels, I provide a resistance device which is preferably in the form of a frictional device. In order to accomplish this, I provide the lower end of the sleeve 38 with serrations or teeth 42 and these teeth mesh with corresponding teeth on the upper side of a small disc 43 guided to move vertically in a guide-cap 44 and pressed up by a coil spring 45 so as to hold the teeth in mesh with each other.

The disc 43 has a dog 46 on its edge which is received in a groove 47 in the wall of the cap to prevent the disc from rotating. This disc seats against a shoulder 48 formed on the lower end of the stem 27. The teeth 42 project in such a direction that they will positively prevent a rotation of the sleeve 38 in a clockwise direction, and they will offer substantial frictional resistance to the rotation of this sleeve 38 in an anti-clockwise direction, such as that indicated by the arrow in Figure 7. Hence, when the counter wheels 6, 7 and 8 are being set forwardly by rotating the stem 27 in a clockwise direction, the disc 43 will frictionally prevent rotation of the inner sleeve or pick-up shaft 21 in the forward direction. Furthermore, if the stem 27 is shoved inwardly, the shoulder 48 will move the toothed disc 43 down and permit the sleeve 38 to rotate freely in order to impart a forward rotation to the pick-up shaft 21 in resetting the number wheels to zero by means of the thumb-head 26. In addition to this, if backward rotation of the gear wheel 9 should occur by backing the automobile, and backward rotation is thereby imparted to the number wheel 8, this backward rotation cannot rotate the pick-up shaft 21 in a backward direction because a rotation of the pick-up shaft in this direction would involve the rotation of the sleeve 38 in a

clockwise direction; this would be positively prevented by the teeth on the disc 43.

Figure 9 shows the construction of the extension sleeves 31 and 35 at the point 32 where they form a joint with the sleeves 20 and 21. In order to form this joint, the extension sleeves 31 and 35 are formed with diametrically opposite tongues 31* and 35* which are received in corresponding slots 10 formed in the ends of the other sleeves.

It is understood that the embodiment of the invention described herein is only one of the many embodiments my invention may take, and I do not wish to be limited 15 in the practice of my invention nor in my claims, to the particular embodiment set forth.

What I claim is:—

1. The combination with mileage indicating numeral wheels, of an operating spindle, 20 a pair of sleeves thereon, means connecting one of said sleeves with said numeral wheel to restore it to zero position, and means connecting the other of said sleeves with 25 said numeral wheel to move the latter to any desired position.

2. The combination with mileage indicating numeral wheels, of an operating spindle, 30 a pair of sleeves thereon, means connecting one of said sleeves with said numeral wheel to restore it to zero position, means connecting the other of said sleeves with said numeral wheel to move the latter to any desired position, and means rendered operative by a longitudinal movement of said 35 spindle for rotating either of said sleeves.

3. In combination, a numeral wheel, a shaft supporting the same, a pair of sleeves surrounding said shaft, a carrying gear and 40 a driving gear turning with said numeral wheel, a pawl and ratchet mechanism between said driving gear and said numeral wheel, said driving gear rotating with the outer of said sleeves, a pawl and 45 ratchet mechanism associated with said carrying gear and co-operating with the inner of said sleeves, and manually operated means for rotating either of said sleeves at will.

4. A resetting attachment for speedometers, comprising a support, a longitudinally movable spindle, a pair of sleeves surrounding said spindle, a pin on said spindle for engaging either of said sleeves, yielding ratchet mechanism also associated with said 55 spindle for preventing rotation of the latter in one direction, and means for moving said spindle longitudinally and rotating the same to cause the rotation of either of said sleeves.

5. A resetting attachment for speedometers, comprising a housing, a spindle slidably and rotatably mounted therein, a spring surrounding said spindle, a ratchet plate engaged thereby, a plurality of sleeves surrounding said spindle, said sleeves having

their adjacent ends provided with oppositely disposed ratchet teeth, a pin on said spindle arranged between said ratchet teeth and normally disconnected therefrom, an end of one sleeve being provided with ratchet teeth engaging those on said plate, and a knurled wheel mounted on said spindle. 70

6. A resetting attachment for speedometers, comprising a housing, a spindle slidably and rotatably mounted therein, a spring surrounding said spindle, a ratchet plate engaged thereby, a plurality of sleeves surrounding said spindle, said sleeves having their adjacent ends provided with oppositely disposed ratchet teeth, a pin on said spindle arranged between said ratchet teeth and normally disconnected therefrom, an end of one sleeve being provided with ratchet teeth engaging those on said plate, a knurled wheel mounted on said spindle, 75 a gear mounted on each of said sleeves, and a pair of concentrically arranged sleeves each having a gear co-operating with one of said first mentioned gears. 80

7. In a resetting mechanism for a register, 90 the combination of a plurality of number wheels including a lowest-denomination wheel, a sleeve carrying the lowest-denomination wheel, driving means including a one-way driving connection for imparting 95 the regular forward driving movement to the lowest-denomination wheel, a rotatable pick-up shaft mounted within the outer sleeve, a hand-operated rotatable member mounted so as to shift into two positions, 100 means for driving the outer sleeve when the hand-operated rotatable member is in one position to rotate the outer sleeve and the lowest-denomination wheel in the forward direction, means actuated by the hand-operated rotatable member in its other position for rotating the pick-up shaft in a forward 105 direction, a pick-up device corresponding to each number wheel, means on the pick-up shaft co-operating therewith when the same is rotated in the forward direction to hold the number wheels with their zeros aligning together, thereby enabling the hand-operated member to reset the number wheels to zero, and means co-operating with the pick-up shaft to prevent rotation of the same in a forward direction when the outer sleeve is being rotated in that direction, and also operating to prevent rotation of the pick-up 110 shaft in a backward direction through the said one-way driving connection when the said driving means is driven in a backward direction. 115

8. In a resetting mechanism for a register, 120 the combination of a plurality of number wheels including a lowest-denomination wheel, a sleeve carrying the lowest-denomination wheel, driving means including a one-way driving connection for imparting 125 the regular forward driving movement to the regular forward driving movement. 130

- any desired reading, a second driving gear wheel co-axial with the last named driving gear wheel and meshing with the second named pinion for rotating the inner sleeve also in the forward direction, a hand-operated rotatable member having a stem mounted to shift into two positions and having means for connecting the same to either of the driving gear wheels according to its position, a spring and means co-operating therewith and with the second named driving gear for preventing the rotation of the inner sleeve when the outer sleeve is being rotated.
12. In a resetting mechanism for a register the combination of a plurality of number wheels including a fraction wheel, an outer sleeve corresponding to the fraction wheel, means for driving the fraction wheel in a forward direction from the sleeve, a pinion carried by the sleeve for rotating the same, an inner sleeve having a pinion for rotating the same, and rotatably mounted in the outer sleeve, a resetting disc corresponding to each number wheel and mounted so as to be rotated by the inner sleeve, each disc having a notch, a pawl corresponding to each number wheel to co-operate with the notch whereby the rotation of the inner sleeve in the forward direction will engage each notch with its corresponding pawl to align the corresponding numbers of the number wheels and enable the number wheels to be rotated in unison to their zero position, a driving gear wheel meshing with the first named pinion to enable the fraction wheel to be rotated in the forward direction to set the number wheels of the register to any desired reading, a second driving gear wheel co-axial with the last named driving gear wheel and meshing with the second named pinion for rotating the inner sleeve also in the forward direction, a hand-operated rotatable member having means for connecting the same to either of the driving gear wheels, a ratchet device associated with the second named driving gear and having teeth projecting in a direction to prevent rotation of the inner sleeve in a direction opposite to that in which the number wheels rotate during their registering movement.
13. In a resetting mechanism for a register, the combination of a plurality of number wheels including a fraction wheel, an outer sleeve carrying the fraction wheel, a driving gear adapted to be driven to drive the register, and loosely mounted on the outer sleeve, a driving connection between the gear and the fraction wheel for driving the number wheel in a forward direction, an inner sleeve, a resetting disc corresponding to each number wheel and carried by the inner sleeve, each disc having a notch therein, a pawl corresponding to each number wheel and co-operating with its corresponding disc whereby the rotation of the inner sleeve engages the notches with the pawls respectively, to align the corresponding numbers on the number wheels, and enabling the number wheels to be rotated in unison by the inner sleeve to reset them to their zero position, a hand-operated rotatable member, means co-operating therewith to effect a driving connection from the hand-operated member to either of said sleeves, and operating in one position to enable the hand-operated member to rotate the outer sleeve in the forward direction to rotate the fraction wheel of the register, and operating in another position to rotate the inner sleeve to actuate the resetting discs to reset the number wheels to zero, and a ratchet device co-operating with the inner sleeve operating frictionally to prevent rotation of the inner sleeve in a forward direction when the outer sleeve is rotated in that direction, and also operating to prevent rotation of the inner sleeve in a backward direction through the said driving connection if the said driving gear is driven in a backward direction.
14. In a resetting mechanism for a register, the combination of a plurality of number wheels including a fraction wheel, an outer sleeve carrying the fraction wheel, a gear loosely mounted on the sleeve adapted to be driven to drive the register, a one-way driving connection between the gear and the fraction wheel for driving the number wheel in a forward direction by the gear, an inner sleeve rotatably mounted within the outer sleeve, a resetting disc corresponding to each number wheel and carried by the inner sleeve, each disc having a notch therein, a pawl corresponding to each number wheel and co-operating with its corresponding disc whereby the rotation of the inner sleeve engages the notches with the pawls, respectively to align the corresponding numbers on the number wheels, and enabling the number wheels to be rotated in unison by the inner sleeve to reset them to their zero position, a hand-operated rotatable member, means co-operating therewith to effect a driving connection from the hand-operated member to either of said sleeves, and operating in one position to enable the hand-operated member to rotate the outer sleeve in the forward direction to rotate the fraction wheel of the register and operating in another position to enable the inner sleeve to be rotated to actuate the resetting discs to reset the number wheels to zero, and means co-operating with the inner sleeve to prevent rotation of the inner sleeve in a forward direction when the outer sleeve is rotated in that direction, and also operating to prevent rotation of the inner sleeve in a backward direction.

- the lowest-denomination wheel, a rotatable pick-up shaft mounted within the outer sleeve, a hand-operated rotatable member mounted so as to shift into two positions, 5 means for driving the outer sleeve when the hand-operated rotatable member is in one position to rotate the outer sleeve and the lowest-denomination wheel in the forward direction, means actuated by the hand-operated rotatable member in its other position for rotating the pick-up shaft in a forward direction, a pick-up device corresponding to each number wheel, means on the pick-up shaft co-operating therewith when the same is rotated in the forward direction to hold the number wheels with their zeros aligning together, thereby enabling the hand-operated member to reset the number wheels to zero, and a frictional-resistance device co-operating with the pick-up shaft to prevent rotation of the same in a forward direction when the outer sleeve is being rotated in that direction, and operating to prevent rotation of the inner sleeve 10 in a backward direction through the said one-way driving connection when the said driving means is driven in a backward direction.
9. In a resetting mechanism for a register, the combination of a plurality of number wheels including a lowest-denomination wheel, a sleeve carrying the lowest-denomination wheel, driving means including a one-way driving connection for imparting the regular forward driving movement to the lowest-denomination wheel, a rotatable pick-up shaft mounted within the outer sleeve, a hand-operated rotatable member mounted so as to shift into two positions, means for driving the outer sleeve when the hand-operated rotatable member is in one position to rotate the outer sleeve and the lowest-denomination wheel in the forward direction, means actuated by the hand-operated rotatable member in its other position for rotating the pick-up shaft in a forward direction, a pick-up device corresponding to each number wheel, means on the pick-up shaft co-operating therewith when the same is rotated in the forward direction to hold the number wheels with their zeros aligning together, thereby enabling the hand-operated member to reset the number wheels to zero, and means co-operating with the inner sleeve to prevent rotation of the same in a forward direction when the outer sleeve is being rotated in that direction, and also operating to prevent rotation of the inner sleeve in a backward direction through the said one-way driving connection when the said driving means is driven in a backward direction.
10. In a resetting mechanism for a register, the combination of a plurality of number wheels including a lowest-denomination wheel, an outer sleeve carrying the lowest-denomination wheel, driving means including a one-way driving connection for imparting the regular forward driving movement to the lowest-denomination wheel, an inner sleeve rotatably mounted within the outer sleeve, a hand-operated rotatable member mounted so as to be shifted into two positions, clutch means co-operating therewith in one of the said positions to effect a driving connection from the hand-operated member to the outer sleeve to enable the outer sleeve to be rotated in the forward direction and thereby rotate the lowest-denomination wheel at will in the forward direction, said clutch means operating in the other position of the hand-operated member to connect the hand-operated member to the inner sleeve and enable the inner sleeve to be rotated by the hand-operated member in a forward direction, a pick-up device corresponding to each number wheel, means on the inner sleeve co-operating therewith when the inner sleeve is rotated in the forward direction, to hold the number wheels with their zeros aligning together, thereby enabling the hand-operated member to reset the number wheels to zero and means co-operating with the inner sleeve to prevent rotation of the same in a forward direction when the outer sleeve is being rotated in that direction, and also operating to prevent rotation of the inner sleeve in a backward direction through the said one-way driving connection when the said driving means is driven in a backward direction.
11. In a resetting mechanism for a register, the combination of a plurality of number wheels including a fraction wheel, an outer sleeve corresponding to the fraction wheel, means for driving the fraction wheel in a forward direction from the sleeve, a pinion carried by the sleeve for rotating the same, an inner sleeve having a pinion for rotating the same, and rotatably mounted in the outer sleeve, a pick-up disc corresponding to each number wheel and mounted so as to be rotated by the inner sleeve, each disc having a notch, a pawl carried by each number wheel to co-operate with the notch whereby the rotation of the inner sleeve in the forward direction will engage each notch with its corresponding pawl to align the zeros of the number wheels with each other, and enable the number wheels to be rotated in unison to their zero position, a driving gear wheel meshing with the first named pinion to enable the fraction wheel to be rotated in the forward direction to set the number wheels of the register to

through the said one-way driving connection if the said driving gear is driven in a backward direction.

15. In a resetting mechanism for a register, the combination of an inner sleeve, a plurality of number wheels, an outer sleeve corresponding to each of the wheels including the wheel of lowest denomination, means actuated by the rotation of the inner sleeve to align the number wheels together in their zero positions, a hand-operated
- 5
10
- stem, means for connecting the same at will to the inner sleeve to reset all the number wheels to zero simultaneously, and means for connecting the stem at will to the outer sleeve of the wheel of lowest denomination to enable the rotation of the stem to advance the number wheels to set the same to any desired reading.

In testimony whereof I have hereunto set my hand.

JOHN L. WHEELER.
